YARN SWIFT

Albert Brügger, Philadelphia, Pa.

Application January 3, 1935, Serial No. 205
In France February 23, 1934

9 Claims. (Cl. 242—110)

My invention relates to the winding of textile fibres and relates particularly to a device suitable for supporting all sizes of skeins of textile fibres or yarns such as rayon, raw silk, organzine, 5 spun silk, cotton, wool or linen.

It is an object of my invention to embody in a swift or reel a plurality of cross-bars comprised of flexible wire arms whereby the cake of yarn may be easily inserted upon the cross-bars.

10 Another object of my invention is to embody flexible cross-bars on a swift, that is adjustable as to its diameter, but when the device is once adjusted it need not be readjusted due to the flexibility of the cross-bars which permit a new 15 skein to be inserted upon the cross-bars.

Another object of my invention is to embody in a swift, cross-bars which support skeins of yarn and which are always equidistant from the center of the swift's axis, thus creating a balanced 20 swift.

Another object of my invention is to construct the parts of the swift so that when the parts are assembled into a completed swift, the swift will be balanced and so it may rotate uniformly.

25 Another object of my invention is to embody in a swift, means whereby the diameter of the swift may be expanded and means for placing a uniform tension on the skein or cake of fibre.

Another object of my invention is to construct 30 parts of a swift which are of a rigid construction, which are interchangeable, and which are easy to assemble.

A further object of my invention is to provide 35 improved means for uniformly tensioning the yarn.

A further object of my invention is to construct the cross-bars so that one end thereof may form a guide for the skein or cake of fibres as 40 the skein is being placed upon the cross-bars.

With the above and related objects in view, my 45 invention consists in the construction and combination of parts as will hereinafter be described in detail, when the detailed description is read in conjunction with the accompanying drawings in which:

Fig. 1 is a perspective view of a swift having a 50 cake of fibre thereon, with the swift mounted to rotate on a vertically extending axis, and a fibre compensating device in engagement with the fibre.

Fig. 2 is an exploded view showing the pertinent elements comprising the swift.

Fig. 3 is an enlarged fragmentary view of the 55 cross-bar members located adjacent the flange.

Fig. 4 is a sectional view of the swift shown in Fig. 1.

Fig. 5 is an enlarged sectional view of the guide and holding plate in normal and in compressed position.

Fig. 6 is a perspective view of one of the flexible cross-arms embodied in the swift shown in Figs. 1 and 4.

Fig. 7 is a sectional view taken on the line 7—7 10 of Fig. 4.

Fig. 8 is a plan view of the guide and holding plate.

Fig. 9 is a sectional view taken on the line 9—9 15 of Fig. 4 showing the reel in expanded position.

Fig. 10 is a fragmentary elevational view illustrating a modified type of swift, a cake holding plate in position, and a means for tensioning the swift comprising a strap and a cooperative weight.

Fig. 11 is a swift showing a modification over Fig. 10 mounted to rotate on a horizontal axis, with a cone which serves to easily guide the ball of yarn which has come directly from the spinning mill.

Fig. 12 is a side elevational view of a modified construction of a flexible holding bar.

Fig. 13 is a side elevational view of another modification of a flexible holding bar.

Fig. 14 is a perspective view of an enlarged 30 plate for retaining the cake on a horizontally positioned swift.

Fig. 15 is a side-elevational view of the plate shown in Fig. 10.

Fig. 16 is a perspective view of a modified device for tensioning the yarn.

Referring now to the drawings, in Figs. 1, 2 and 3 I disclose a swift or reel comprised of a wooden or metal reel, generally designated as A; a plurality of flexible wire cross-bars or cross-arms, each of which is generally designated as B, and which are suitably attached to the reel A; a plurality of combined guides and holding plates, each of which is generally designated as C, which are located at each end of the wooden reel A; and interfitting with the reel A is an axle, generally designated as D, that joins, supports, and rotates each of the plates C; a key, generally designated as E, is adapted to provide relative movement between the reel A and the plates C whereby the diameter of the swift may be optionally expanded or reduced; and a lock nut, generally designated as F, locks the parts hereinbefore generically described in a fixed position.

In Fig. 1 the swift is shown as being mounted on a vertical axis with a skein or cake of yarn, fibre, or thread mounted thereon, which skein has come from the spinning mill. The yarn 5 passes through an eye 10 on one end of a pendulum, generally designated as G, which leans upon the thread due to its pivoted upper end and the fact that it is raised from its lowermost position which it otherwise may assume. The pendulum 10 G compensates for the difference in tension which is produced when the thread is pulled by the mechanism that reels a bobbin (not shown) onto which the thread is wound. By means of the pendulum G, yarn or thread will be rewound upon 15 the bobbin or second reel (not shown) at a uniform tension.

Referring now in greater detail to the elements comprising the swift, illustrated in Figs. 1, 2, and 3, the reel A comprises a hollow nave 12 having 20 flanges 14, 16 attached at each end thereof. Each of the flanges 14, 16 has a plurality of aligned, equi-spaced small openings 18 on the outer flat surface for receiving the ends 20, 21 of each of the cross-bars or cross-arms B, which carry the 25 cake of fibre. Diametrically opposed openings 23, 24 on the flange 16 receive the legs 25, 26 respectively of the key E.

The cross-arm B, on which a skein of yarn rests, is comprised of a single length of pliable 30 wire. The end 21 which interfits with one of the openings 18 on the flange 16 has a right angle portion 27. From the other end of the right angle portion 27, the wire reverses itself to form a substantially parallel thread retainer, designated 35 as 28; the wire is then bent to form a cross-bar 29, which is substantially parallel to the end 21, and a plurality of undulations are formed in the cross-bar 29. The free end, designated as 30, of the cross-bar 29 is bent to run parallel to itself 40 and it also tapers towards the axis of the reel A if the axis of the reel A were extended. The cross-arm is continued to run parallel to the cross-bar 29, as at 30A, and then is bent at right angles, as at 31, where the portion 31 is joined 45 to the end 20 which interfits with the opening 18 on the flange 14. The ends 20, 21 are in alignment, although spaced apart, and form pivots about which the cross-arm B oscillates. When the cross-arms B are assembled upon the reel A, 50 the bent portions 30 converge to form substantially a truncated cone, as is illustrated in Figs. 1 and 4, whereby the placing of the cake of thread on the swift is facilitated, particularly since the cone portions of the cross-bars are flexible and 55 may be bent inwardly. The swinging of the cross-bar B about its pivoted ends determines the distance of the cross-bar 29 from the center of the swift.

As the end 30 of the cross-bar is located a 60 comparatively long distance from its nearest supporting end 20, it is comparatively flexible as compared to the thread retainer 28. Thus, a cake of yarn may be pushed upon the truncated cone, which is flexible and responds to the pushing force of the cake of yarn. When the arms B are adjusted for a particular size of cake, it need 65 not be re-adjusted when another cake is placed thereon.

Although the cross-bar B has been described as 70 applicable to an adjustable reel, the cross-bar B may also be advantageously embodied in a reel that is not adjustable in diameter.

Each of the combined guide and holding plates 75 C are identically constructed and therefore only

one plate will be described. The plate C, placed to interlock the cross-arms and the reel A, is comprised of a metal stamping having a circular disc portion 33, and the periphery of the disc portion is bent to form a flange 35. The internal 5 diameter of the flange 35 is slightly in excess of the diameter of each of the flanges 14, 16 in order that the flanges will overlap. A plurality of equi-spaced peripheral slots 37 are cut into the flange 35 and into the extremity of the disc portion 33. 10 The center of the disc is cut away to form an aperture 38 which has two radially extending slots 39. Although two slots are disclosed but one slot is necessary. Within the flat disc are two arcuate slots 40, 41 which permit the legs 15 25, 26 of the key E to move the reel A when the plate C is interposed between the key and the reel A. Surrounding the aperture 38 and its connecting slots 39 on the disc 33 is a bead 43. The inner surface of the bead is adapted to tightly 20 press against the exterior flat wall of the flange, in order to lock the device in a definite position, as shall hereinafter be described.

However, a plurality of finger flanges or grips 25 may be integrally formed with the plate C to hold the plate during the turning of the key E. The finger flanges, it is to be observed, should extend in the opposite direction to the flange 35. The axle D has a central bore 50 which extends 30 partially through the longitudinal axis of the axle. The bore serves as a journal for the swift. Diametrically positioned wings 52 of metal are rigidly attached as part of the axle and a boss 54 on each wing prevents the movement of the axle through the aperture 38 and the slots 39 on 35 the plate C. The other end is threaded, as at 56, to receive a locking wing nut F.

Interposed between the plate C and the locking nut F is the key E. The key is comprised of a metallic stamping wherein parallel extending legs 40 25, 26 are formed from the body portion 56. A central aperture 58 is formed in the body portion for the passage of the axle D and concentric with the aperture 58 are two arcuate flanges 60, 61, which flanges are adapted to press against the 45 disc 33 of the plate C whereby the cross-arms B will be locked in position.

A vertically positioned shaft or pivot 64 interfits with the bore 50 of the axle and serves as the support about which the swift rotates. The 50 shaft 64 is threaded at one end and retains a cup 66 which is held in position by virtue of nuts 68, 69 pressing washers against the flat portion 70 of the cup 66. The threaded end of the shaft is of sufficient length to pass through an aperture 55 in a supporting bracket 72 where a nut 74 holds the shaft on the bracket 72.

The cup 66 serves a dual purpose of preventing 60 loose thread from encircling the shaft 64 and, also, serves as a support for the shaft. The cup 66 for most effective service should be raised sufficiently so that the lip of the cup surrounds the nut F.

A strip of wire 74, bent in the form of a circle with each end formed as a hook to overlap the 65 body of the wire, provides an additional strengthening support for the bars B and is arranged to lie adjacent the junction of the portions 27, 28 of the cross-arm. The wire 74 also prevents the 70 yarn from catching in parts of the cross-arms and is expandible in a manner to follow the extension and the folding of the cross-arms.

A summary of the assembly and of the operation of my invention is as follows:—

The cross-bars B are assembled upon the 75

wooden or metal reel A so that each cross-bar is inclined in the same direction as is illustrated in Fig. 7. The plates C are placed in position so that the portions 27 and 30A of each cross-bar 5 are interfitting with the peripheral slots 37 on the plates C; however, the plate C, which is placed upon the flange 16, must be located so that the arcuate slots 40, 41 permit the key E to be turned a distance equal to the length of each of the arcs 10 in order to extend the diameter of the swift from a minimum value to a maximum value.

The axle D is next inserted through the opening in the plate C, the opening in the nave 12, and the opening in the second plate C. The 15 key E is slipped over the threaded end of the axle so that the openings 23, 24 in the flange register with the fingers 25, 26 of the key. The wing nut F is then screwed upon the threads 56 of the axle D.

20 To alter the diameter of the swift, the nut F is loosened and the key E is turned while both of the plates C are held firmly, as the above operation is performed the cross-bars B are shifted by sliding in the slots 37 from the minimum 25 diameter, shown in Fig. 7, to the maximum diameter, shown in Fig. 9, or to any intermediate diameter. The nut F is then turned to hold the plates C firmly against the flanges of the reel A, see Figs. 4 and 5, whereby the diameter 30 of the swift is fixed. With a cake of yarn in position on the swift, the swift is placed upon the vertically extending shaft and a thread Y is unwound and passed through the eye 10 which has a face of porcelain and over a loose 35 running pulley 80 comprised of porcelain.

After the swift is once adjusted in diameter, it is not necessary to alter the diameter just so long as skeins of the same diameter are to be used. The second skein is merely pushed upon 40 the cone shaped portion of the cross-bars and the inherent resiliency of the cross-bars adjust themselves to the skein of yarn.

Referring now to Fig. 11 I disclose another modification of my invention.

45 The variable diameter swift, generally designated as H, is adapted to be mounted upon a horizontally extending axis 90. A tension weight or brake, for holding the yarn taut, may be placed upon a pulley 92 located adjacent one 50 end of the shaft 90 or a weight 94 may be hung by a strap 96 on the nave 98 of the swift A'. The size of weight may be varied to suit different conditions.

A modified type of cross-bar, generally designated as J, is comprised of metal wire, as is 55 illustrated in Fig. 13. The cross-bar H has an inturned tip 100 and an upstanding portion 102, which is connected at one end to the tip 100, and its other end 104 is reversely bent to 60 run parallel to the portion 102 for a short distance. A cross-bar 106, extending at substantially a right angle, proceeds from the portion 104, and the cross-bar 106 has a plurality of ripples therein to prevent the loosening of the 65 fibre or yarn. The end of the cross-bar 106 is formed into a holding member, designated as 108, which is shaped similar to the portions 102, 104 but of smaller size in order to serve as a support, at the time of the introduction of a 70 cake of yarn, for the interior surface of a cone-shaped funnel, generally designated as K. The funnel guides the central portion of the cake of fibre upon the cross-arms so that the interiorly located fibres do not catch upon any protrusions and so break any of the fibres.

The wire continues from the portion 108 to an arm 109, which is parallel to the arm 102, and the arm's tip 110 is inturned to be aligned with the tip 100.

The swift H may be actuated and adjusted 5 in a manner similar to the vertically positioned swift shown in Fig. 1, and since the construction is similar no detailed description will be entered into.

To prevent the slipping of the cake of yarn from 10 the swift, I place a detachable metallic flange, generally designated as L, on the holding and guide plate C, see Fig. 10. The extended arm 104 prevents the cake of yarn from slipping by 15 the other end of the swift.

The detachable metallic flange L is formed on a stamping press and has a circular flat disc-like peripheral portion 112. A bead 114 formed near the periphery strengthens the disc-like portion. Converging ridges 116 on the disc-like portion also strengthen the plate. An internal flange 118 is adapted to tightly fit upon the outer circular flange of the plate C, and an offset 120, parallel to the portion 112, limits the inward movement of flange L. Extending outwardly 20 from the offset 120 are diametrically positioned projecting ears 121, 122 in order to grasp the flange while it is to be inserted on the plate C or it is to be removed. A plurality of slots 124 are disposed in the flange 118 and the flat portion 112 in order to permit the cross-arms to be 25 expanded without any hindrance from the side flange L. During the machine stamping operation in forming the detachable flange L, a small portion of the metal 126, adjacent the flange 118, 30 is pressed outwardly so that the metal 126 is substantially coplanar to the flange. A slight bevel is formed on the metal extension 126 so that it will easily slide on or off the flange of the 35 plate C.

The detachable flange L may be constructed either for the left or the right hand side, the only difference between the two flanges is in the inclination of the slots through which the cross-arms pass, the slots in one flange being inclined in 40 one direction and the slots in the other flange being inclined in another direction.

In Fig. 12, I disclose a modified construction of the cross-bar which is generally designated as M. The construction is similar to the cross-bar 45 illustrated in Fig. 13, except that the right-hand portion of the bar M forms a right angle. The cross-bar may, also, be constructed without the ripples in the cross-arm on which the fibres rest.

In Fig. 16 a simplified device for tensioning the 55 yarn Y is illustrated. The yarn Y passes from the adjustable diameter swift to a bobbin N and is held away from the bracket 72 by means of a suitably located eye-hook 132. A compensator comprised of a cylindrical wire 134 has its ends 60 136, 137 bent at right angles to the main body portion, and the ends extend in opposite directions but in the same plane.

The end 137 is located so that it is not in its extreme downward position, but it is permitted 65 to rest upon the yarn so that the yarn is tensioned.

In Fig. 11 I disclose the modified type of axle 90 of polygonal cross-sectional formation. A spring leg pin 152 is located to limit the movement of the plate C when the lock nut F is unloosened; otherwise, the plates C would separate from the flanges of the reel as well as separate from the cross-bars. The pin 152 interfitting 70 with a groove on the axle 90, thus prevents the 75

annoying experience of having the swift H from becoming disassembled. The left hand end of the axle 90 has means (not shown), such as an extruded portion, to limit the movement of the 5 plate at the left hand side.

The pendulum G, shown in Fig. 1, is mounted upon one end of a bracket 154, and the other end of the bracket is held between the base 70 of the cup and the bracket 72.

10 Although my invention has been described in considerable detail, such description is intended as illustrative rather than limiting, since the invention may be variously embodied, and the scope of the invention is to be determined as claimed.

15 I claim as my invention:

1. An adjustable diameter swift comprising a reel having a flange at each end thereof, and one flange having an opening near its periphery, a plurality of cross-bars pivotally mounted upon 20 the flanges of the reel, a plurality of plates, each plate having a plurality of recesses therein and being located adjacent each flange whereby a recess interfits with a portion of the cross-bar, a shaft having a central bore whereby the bore 25 may function as a bearing, said plates being mounted upon the said shaft and keyed together so that they rotate in unison, a key loosely mounted upon said shaft, an extension on said key and interfitting with the opening on one of 30 the reel flanges whereby the reel and the key may be rotated with respect to the plates in order to oscillate the cross-bars about their respective pivots so that the diameter of the yarn carrying cross-bars is increased or decreased.

35 2. The subject matter as set forth in claim 1, and a pivot interfitting with the central bore of said shaft and about which pivot the reel is rotatable.

3. A demountable end plate of stamped metal 40 sheeting adapted to be placed upon one end of a swift comprising a disc, a bead formed on said disc to strengthen said disc, a plurality of angularly disposed openings therein being adapted to receive and guide swift cross-bars, and an inner flange adapted to firmly set upon one peripheral rim of said swift.

4. A demountable end plate of stamped metal sheeting adapted to be placed upon one end of a swift comprising a disc, a bead formed on said 50 disc to strengthen said disc, a plurality of angularly disposed openings therein being adapted to receive and guide swift cross-bars, an inner flange adapted to firmly set upon one peripheral rim of said swift, and a plurality of members cut 55 from said disc and which extend parallel to said inner flange.

5. A demountable end plate of stamped metal sheeting adapted to be placed upon one end of a swift comprising a flat inner disc, means to 60 strengthen said plate, a plurality of angularly disposed slots in said plate therein, said slots being adapted to receive and to guide swift cross-bars, means to grasp a peripheral rim of said swift, and means for an operator to hold 65 said plate, said means being located to extend on the outside surface of said plate.

6. A demountable guide and holding plate of 70 stamped metal sheeting for an adjustable diameter swift comprising a circular disc having a central opening, a flange on the inner peripheral portion of said circular disc, a plurality of equi-

spaced peripheral notches on the flange and the inner extremity of the disc portion, each of said notches being adapted to receive a portion of a cross-bar whereby the cross-bar is guided, and a bead on said disc adjacent said central opening. 5

7. A yarn swift comprising a reel having a flange at each end thereof, each flange having a plurality of openings therein, a plurality of wire supporting members having their ends interfitting with aligned openings in the reel flanges, 10 each of said supporting members being substantially rigid on one end and comparatively flexible on the other end of the swift whereby a cake of yarn may easily be placed upon the supporting members, each supporting member being substantially parallel to the axes of the reel between the flanges, and the flexible end of the supporting member extending for a distance greater than that necessary to support the cake and converging whereby the cake of yarn may be guided 15 upon the supporting member and means for adjusting the diameter of said supporting members, said means comprising a plurality of plates having peripheral openings therein which receive a portion of the supporting members whereby movement of the plate oscillates the supporting members from their pivotal point, a shaft connecting the said plates, a key mounted upon one end of said shaft and interfitting with a cooperative opening in one of the flanges of 20 the reel whereby the reel may be moved with respect to the end plate for adjusting the diameter of the yarn carrying wire supporting members, and a lock-nut for holding the end plate, the shaft, and the spool rigidly together. 25

8. A yarn reel comprising a reel having a flange at each end; each flange having a plurality of equi-spaced openings therein and said openings in one flange in alignment with similar openings in the other flange; a plurality of cross-bars; each 40 cross-bar comprising a piece of wire formed to include a portion extending outwardly and then inwardly at substantially a right angle with respect to the axis of said reel whereby a side of a cake of yarn may be supported, said wire continued to extend substantially parallel to the axis of the reel, said wire continued to overlap one end of said reel, said overlapping cross-bars forming a flexible frustro conical member, and each end of said cross-bar fitting into aligned 50 openings in the flanges of the reel whereby each cross-bar is pivotally mounted.

9. A yarn reel comprising a reel having a flange at each end thereof; a plurality of wire cross-bars; each flange of said reel having a plurality of equi-spaced openings therein; the openings in each of the flanges being in alignment; each cross-bar including aligned ends interfitting with the complementary aligned openings in said flanges, a portion of each of said cross-bars extending outwardly and then inwardly at substantially a right angle with respect to the axis of said reel whereby a side of a cake of yarn may be supported, another portion of said cross-bar extending substantially parallel to the axis of the reel, and a portion of each cross-bar overlapping one flange, said last-mentioned overlapping portion of said cross-bar being flexible as compared to the portion of the cross-bar extending at substantially a right angle with respect to the axis of said reel. 60

ALBERT BRÜGGER.
